UNITED STATES PATENT OFFICE.

DON A. MUNGER, OF DETROIT, MICHIGAN.

ELECTRIC SWITCH.

1,300,855.

Specification of Letters Patent. Patented Apr. 15, 1919.

Application filed May 28, 1917. Serial No. 171,363.

To all whom it may concern:

Be it known that I, DON A. MUNGER, citizen of the United States, residing at Detroit, county of Wayne, State of Michigan, 5 have invented a certain new and useful Improvement in Electric Switches, and declare the following to be a full, clear, and exact description of the same, such as will enable others skilled in the art to which it 10 pertains to make and use the same, reference being had to the accompanying drawings, which form a part of this specification.

My invention relates to an electric switch shown in the accompanying drawings and 15 more particularly described in the following specification and claims.

One object of my invention is to provide means for opening and closing an electric circuit consisting of one or several paths, 20 as may be necessary to accomplish the desired purpose.

Another feature of the invention is the iron magnet case, which completely surrounds the magnet, in such manner that 25 when the armature is attracted by the magnetic pull, not a partial but a completely closed magnetic circuit is formed on all sides of the winding.

A further object of the cast iron magnet 30 case is to dissipate any heat generated by the coil by conduction through the core and magnet case.

Another object in completely surrounding the magnet with an iron case is that a sluggish, quiet and powerful attraction for the 35 armature is obtained.

Another object of the iron case is the protection of the magnet winding from mechanical or other injury.

Another feature of the invention is that 40 each blow-out shield revolves radially about its support when necessary to change contacts.

With the foregoing and other objects in 45 view, which will appear as the description proceeds, the invention resides in the combination and arrangement of parts and in the details of construction hereinafter described and claimed, it being understood 50 that changes in the precise embodiment of the invention herein disclosed, may be made without departing from the spirit of the same.

In the drawings:—

Figure 1 is a front elevation of the switch.

Fig. 2 is a side elevation of the switch showing the pivoted arm in its "open" position.

Fig. 3 is a side elevation with the arm "closed." 60

Referring now to the letters of reference placed upon the drawings:—

A, denotes a slate panel. B, indicates a cast iron coil retaining case secured to the panel by bolts B'. C, indicates a magnet winding, and C', its core. D, designates a swinging cast iron arm or armature pivoted to lugs b, at the bottom of the coil retainer case. The arm D, is free to swing through an arc limited in one direction by a lug d, 70 integral with the arm which strikes the outer side of the coil retainer case when said arm is in its "open" position;—the arm contacting with a brass non-sealing screw E, lodged in the core C', when in its "closed" position. 75

Cast integral with the swinging arm is a circular disk D', of suitable thickness which when in closed position leaves an airgap of about two-thousandths of an inch between the disk and the iron coil retainer or magnet case B;—thus a magnetic circuit may be formed through the core; cast magnet case; across the slight air gap; through the cast disk of the swinging arm; and back to the core. 80

This circuit, flowing as it does to each and every point, provides a strong magnetic pull, because not only the core attracts the arm and disk, but the outer shell of the magnet case as well, thus forming a completely closed circuit. 85

Because of this completely closed magnetic circuit, the closing of the arm is quiet as the magnetic pull increases as the arm approaches the core and iron case, and after the arm is in closed position no rebound can take place because of the intense attraction of the core and case for the arm and disk. 90

The lower end of the arm D, is provided with an aperture D², to receive a transverse rod (not shown) or other suitable connecting element, adapted to couple a plurality of the switches together that they may operate in conjunction. 95

Pivoted to a lug integral with the swinging arm D, at its upper end, is an arm F, which carries a copper contact G, secured thereto. H, is a rod extending through holes in the swinging arm D, and the arm F, having a T-shaped head lodged in a recess 100 105

formed in the swinging arm for its reception. Sleeved upon the rod H, is a spring I, held in proper position between two caps I', carried by the rod. F' is a lug on the arm 5 F, adapted to bear against the swinging arm, to limit the action of the spring I. F², is a flexible shunt connecting the arm F, with the magnet case or lug b, supporting the swinging arm. G', is a stationary contact supported on the end of an arm J, bolted to the slate panel. K, is an electric terminal connected by a bolt with the arm J. To prevent burning of the contacts by an arc caused by opening contacts G and G', a 10 blowout coil L, is provided mounted on the rear of the panel. This coil consists of several turns of wire wound on a spool and mounted on an iron core L'; each end of this core is connected to an iron rod L², running 15 through the slate panel terminating in two cast iron ears M, secured to the rods by set screws m.

These cast iron ears are disposed on each side of the contacts G and G'. An asbestos 20 shield N, is secured to the cast iron ears M, to prevent burning by the arc when contacts are broken.

As mentioned before, the swinging arm or armature, is attracted by the core and magnet case because of the magnet coil surrounding the core and inclosed by the case. This coil consists of many turns of fine copper wire through which a current is passed which causes the desired magnetic pull. The 25 lead wires of this coil pass through hard rubber bushings b', which protect them from chafing. These wires terminate at copper terminals O, and are known as the control circuit terminals. The other circuit from K 30 to K', is the heavy or working circuit which is to be controlled. When both contacts G, and G', are closed an electric circuit is formed starting at terminal K, through bolt to arm J, across copper contacts G and G', 35 through arm F, to swinging arm or armature D, (also by way of flexible shunt F²) to magnet case B; through bolts holding case to slate panel; to wire connecting series blowout L; and out at other terminal K'.

50 It will be readily seen that when contacts G, and G', are opened the circuit will be broken.

As long as an arc is maintained across the contacts G, and G', current is flowing through the blowout coil L. A magnetic

flux is set up in the iron core of the blowout 55 coil, flowing through the iron rods L², to the ears M, and across from tip to tip of ear through the arc, thereby extinguishing it.

Having thus described my invention, what I claim is:

1. An electric switch including circuit closing contacts, a fixed bracket having one of the contacts mounted on it, a pivoted armature, a yieldably mounted arm carried by the armature and having the other of said contacts mounted on it, means for closing the switch, rods supported intermediate of their ends and provided at one end with blades located at opposite sides of the said contacts, said rod and blades being of magnetic material and a blow-out coil magnetically connected with and supported by the rods at the other end thereof.

2. An electric switch comprising a supporting panel, a bracket mounted on the 75 panel, a pivoted armature, a yieldably mounted arm carried by the armature, circuit closing contacts mounted on the said bracket and arm, means for closing the switch, rods extending through the panel, 80 plates carried by the rods at one end thereof and located at opposite sides of the contacts, said rods and plates being of magnetic material and a blow-out coil magnetically connected with and mounted upon the rods and 85 located at opposite sides of the panel from that at which the contacts are arranged.

3. An electric switch including a panel, rods extending through the panel and provided with means for adjustably engaging 90 the same, a blow-out coil magnetically connected with and mounted upon the rods in rear of the panel, an armature pivotally mounted at the front of the panel, a bracket mounted on the panel above the rods, a 95 yieldably mounted arm carried by the armature, circuit closing contacts mounted on the bracket and on the said arm, and plates located at opposite sides of the contacts and adjustably mounted on the rods at the front 100 ends thereof, said rods and plates being of magnetic material.

In testimony whereof I sign this specification in the presence of two witnesses.

DON A. MUNGER.

Witnesses:

S. E. THOMAS,
N. H. HOUSE.
